UNITED STATES PATENT OFFICE.

JEAN F. WEBB, OF NEW YORK, N.Y.

AIR-ANCHOR FOR PARACHUTES.

1,055,245.

Specification of Letters Patent.

Patented Mar. 4, 1913.

Application filed March 8, 1911, Serial No. 613,050. Renewed August 24, 1912. Serial No. 716,883.

To all whom it may concern:

Be it known that I, JEAN F. WEBB, residing at New York, in the county of New York and State of New York, have invented 5 a new and Improved Air-Anchor for Parachutes, of which the following is a specification.

My invention is an improved air anchor for use particularly in connection with air 10 ship emergency sustaining parachute devices such for example, as is disclosed in my copending application, filed Oct. 17, 1910, Ser. No. 587,502.

Primarily the invention has for its object 15 to provide a quick opening anchor that can be compactly folded up when not in use and will be strong and light in its construction.

The invention also includes those novel 20 details of construction, combination and arrangement of parts all of which will be first fully described and then be specifically pointed out in the appended claims, reference being had to the accompanying drawing, in which,

25 Figure 1, is a side elevation of the air anchor in use. Fig. 2, is an enlarged central section of the air anchor frame, the same being shown open in full lines and partly closed in dotted lines. Fig. 3, is a 30 view of the parts shown in Fig. 2 folded up. Fig. 4, is a section on the line 4—4 of Fig. 2. Fig. 5, is a top plan view of the top of the anchor frame. Fig. 6, is a detail perspective view of the rib opening spring plate 35 and one of the springs. Fig. 7, is a view similar to Fig. 2, of the anchor frame open and showing a slight modification, the cover being omitted. Fig. 8, is a view showing the frame of Fig. 7, folded up. Fig. 40 9, is a detail plan view of the upper spring cup and rib rack.

In the accompanying drawing in which like numerals and letters of reference indicate like parts in all of the figures, it will 45 be noticed that a central rod 19 has a ring 20 at its lower end for the cable 11, and is provided with a cup-like casing 21 near its lower end into which a coil spring 22 on the rod 19 projects.

50 23 designates a collar that is mounted on the rod 19 between which and the spring casing 21 the spring 22 is held; a stop 24 being provided on the rod 19 to limit the

upward movement of the collar 23 under the influence of the spring 22. 55

At the upper end the rod 19 has a fixture 34 having bearings 35 in which the rib sockets 36 are hinged as at 38, stops 37 limiting the opening movement of the ribs 31. The ribs 31 are made of ash, or other suitable material that will be light, strong and flexible, and they are fitted into and secured to the sockets 36. At their outer ends the ribs 31 have socket members 29 over the buttons 30 of which the covering 42 is fastened. Hinged to the collar 23 at 26 are brace members 25 each of which is composed of two sections that are hinged together at 27, one section being hinged at 26 to the collar 23 and the other section being hinged 70 at 28 to the socket 29.

Each rib 31 has a stop shoulder member 32 in the recess 33 of which the hinge joint 27 of the respective brace is adapted to lie when the parts are folded up, as shown in 75 Fig. 3.

In order to open the ribs 31 fully, coil springs 41 are mounted in slots 40 of a ring 39 that is fastened to the rod 19 near the top end of the same, one end of which 80 spring 41 being held against the rod 19, while its other end engages a rib 31 to continuously tend to "open up" the frame. The anchor frame thus formed is covered by a suitable cover 42 which is sewn to the 85 ribs 31 and has a central opening over which the mouth of a balloon bag 43 may be secured, a suitable cord mesh being fitted over the whole to strengthen the anchor.

In practice either the spring 41 or the 90 spring 42 may be omitted, or both may be used, if desired, so long as a quick initial opening of the anchor is obtained.

In practice the air anchor cable 11 is connected to the parachutes (not shown). 95 When the parachutes and anchor are not in use, they are folded up, the anchor being folded as in Fig. 2 and held in a suitable carrying case (not shown). When it is desired to bring the anchor into play, the operator releases the holding means of the case to permit the anchor to be ejected, whereupon the springs 22 and 41 immediately open the anchor, thus permitting the air to enter the same. The anchor thereupon acts 100 as a drag to pull the parachutes into position.

tion. When the balloon bag 43 is employed it fills with air, and thus adds to the dragging effect of the device.

The foregoing described matter and the forms shown in Figs. 1 to 6 inclusive is divided out of my co-pending application hereinbefore referred to.

In Fig. 7, *et seq.* I have shown a slight modification of the invention. In this form 10 I omit the torsion springs of the other form, and in lieu thereof I provide a cup 1 on the rod, which has radial lugs 2 to form rib receiving spaces 3, there being one for each rib, and into which the ribs may be 15 folded when the anchor parts are in the position shown in Fig. 8. The cup 1 is pinned to the rod, and a spring 4 projects into the cup and engages a sliding collar 5 to which the rods 6 are pivoted, as at 7, the 20 outer ends of the rods 6 being pivoted at 8 to the ribs. The upwardly movement of the collar 5 is limited by a fixed stop 9 on the rod. In this form of the invention the operation is essentially the same as in the other 25 form, excepting that in lieu of the torsion springs of the other form the coil spring arrangement is substituted.

From the foregoing description taken in connection with the accompanying drawings, 30 it is thought the complete construction, operation and advantages of my invention will be readily apparent to those skilled in the art to which the invention appertains.

What I claim is:

1. An air anchor, a cable depending therefrom for suspending a flying machine and a parachute on said cable, said anchor comprising an umbrella like frame and a cover therefor, said cover having an opening, and 40 a balloon bag having its mouth secured over said opening.

2. An air anchor that includes a rod, ribs hinged thereto, braces for said ribs, means for opening said ribs and a cover for said ribs, said cover having a central opening and a bag having its mouth secured over said opening.

3. An air anchor that includes a rod, a fixture at one end of said rod, ribs hinged to said fixture, a collar slideable on said rod and braces connecting said ribs and said collar, said braces being composed of two sections hinged together and a cover for the whole together with a radially slotted fixture on said rod to receive said braces when said anchor is folded up.

4. An air anchor that includes a rod, a fixture at one end of said rod, ribs hinged to said fixture, a collar slideable on said rod and braces connecting said ribs and said collar, said braces being composed of two sections hinge jointed together, stops on said ribs to receive said hinged joints of said braces as said anchor is folded shut, and a cover for the whole.

5. In an anchor, an umbrella-like frame including a central rod support, ribs hinged thereto, a frame cover over said ribs, said cover having an opening and a balloon shaped bag secured over said opening.

6. An air anchor that includes a central rod support, a fixture secured at one end to said support, rib sockets hinged to said fixture, ribs mounted in said rib sockets, spring devices on said rod to engage said ribs to "open" the same, a slideable collar on said rod and braces connecting said collar with said ribs, stops on said fixture for limiting the opening movement of said ribs, and a frame cover over said ribs.

7. An air anchor that includes a central rod support, a fixture secured at one end to said support, rib sockets hinged to said fixture, ribs mounted in said rib sockets, spring devices on said rod to engage said ribs to "open" the same, a slideable collar on said rod, sockets fitted on the free ends of said ribs, braces connecting said collar with said rib end sockets, a spring on said rod continuously tending to force said collar in a direction to open said ribs, and a frame cover over said ribs.

8. An air anchor that includes a central rod support, a fixture secured at one end to said support, rib sockets hinged to said fixture, ribs mounted in said rib sockets, spring devices on said rod to engage said ribs to "open" the same, a slideable collar on said rod, sockets on the free ends of said ribs, braces connecting said collar with said rib end sockets, a spring on said rod continuously tending to force said collar in a direction to open said ribs, said braces each including a pair of members hinged together, and a frame cover over 100 said ribs.

9. An air anchor that includes a central rod support, a fixture secured at one end to said support, rib sockets hinged to said fixture, ribs mounted in said rib sockets, spring devices on said rod to engage said ribs to "open" the same, a slideable collar on said rod and braces connecting said collar with said ribs, a spring on said rod continuously tending to force said collar in a direction to open said ribs, said braces each including a pair of members hinge jointed together, stops on said ribs to engage the hinged joint of the respective braces when said ribs are folded together, and a frame cover over 110 said ribs.

10. An air anchor that includes a central rod support, a fixture secured at one end to said support, rib sockets hinged to said fixture, ribs mounted in said rib sockets, spring devices on said rod to engage said ribs to "open" the same, a slideable collar on said rod, braces connecting said collar with said ribs, and a frame cover over said ribs, said cover having an opening and a 120

balloon-shaped bag secured over said opening.

11. An air anchor that includes a central rod support, a fixture secured at one end to said support, rib sockets hinged to said fixture, ribs mounted in said rib sockets, spring devices on said rod to engage said ribs to "open" the same, a slidable collar on said rod and braces connecting said collar with said ribs, stops for limiting the opening movement of said ribs, and a frame cover over said ribs, said cover having an opening and a balloon-shaped bag secured over said opening.

15. 12. An air anchor that includes a central rod support, a fixture secured at one end to said support, rib sockets hinged to said fixture, ribs mounted in said rib sockets, spring devices on said rod to engage said ribs to "open" the same, a slidable collar on said rod and braces connecting said collar with said ribs, a spring on said rod continuously tending to force said collar in a direction to open said ribs, and a frame cover over said ribs, said cover having an opening and a balloon-shaped bag secured over said opening.

30 13. An air anchor that includes a central rod support, a fixture secured at one end to said support, rib sockets hinged to said fixture, ribs mounted in said rib sockets, spring devices on said rod to engage said ribs to "open" the same, a slidable collar on said rod and braces connecting said collar with said ribs, a spring on said rod continuously tending to force said collar in a direction to open said ribs, said braces each including a pair of members hinged together, stops on said ribs to engage the hinged joint of the respective braces when said ribs are folded together, and a frame cover over said ribs, said cover having an opening and a balloon-shaped bag secured over said opening.

35 14. An air anchor that includes a central rod support, a fixture secured at one end to said support, rib sockets hinged to said fixture, ribs mounted in said rib sockets, spring devices on said rod to engage said ribs to "open" the same, a slidable collar on said rod and braces connecting said collar with said ribs, a spring on said rod continuously tending to force said collar in a direction to open said ribs, said braces each including a pair of members hinged together, stops on said ribs to engage the hinged joint of the respective braces when said ribs are folded together, and a frame cover over said ribs, said cover having an opening and a balloon-shaped bag secured over said opening.

40 45 50 55 15. An air anchor consisting of a central rod support, a spring case mounted on said support near one end, a spring on said rod to enter said case, a collar slidable on said rod against which said spring presses, a stop on said rod to limit the movement of said collar under the influence of said spring, a fixture on the other end of said rod, rib carrying sockets hinged to said fixture, braces pivoted to said ribs and to said collars, said braces consisting of two sections hinged together, spring devices carried by said rod and engaging said ribs, continuously tending to "open" said ribs, and a frame cover secured over said ribs.
